UNITED STATES PATENT OFFICE.

FREDERIC ALBERT PALLÉ, OF NEW YORK, N. Y.

ROTARY ENGINE.

SPECIFICATION forming part of Letters Patent No. 729,399, dated May 26, 1903.

Application filed October 20, 1902. Serial No. 128,004. (No model.)

To all whom it may concern:

Be it known that I, FREDERIC ALBERT PALLÉ, a citizen of France, and a resident of the city of New York, borough of Manhattan, 5 in the county and State of New York, have invented a new and Improved Rotary Engine, of which the following is a full, clear, and exact description.

The object of the invention is to provide a 10 new and improved rotary engine which is simple and durable in construction, very effective in operation, arranged to utilize the motive agent to the fullest advantage and to allow of conveniently reversing the engine 15 whenever it is desired to do so.

The invention consists of novel features and parts and combinations of the same, as will be more fully described hereinafter and then pointed out in the claims.

20 A practical embodiment of the invention is represented in the accompanying drawings, forming a part of this specification, in which similar characters of reference indicate corresponding parts in all the figures.

25 Figure 1 is a cross-section of the improvement. Fig. 2 is a side elevation of the same, parts being broken out. Fig. 3 is a perspective view of the rotary piston and its slideable piston-heads. Fig. 4 is a sectional perspective view of the piston and its shaft, and Fig. 30 5 is a perspective view of one of the piston-heads.

The cylinder A of the rotary engine is mounted on a suitably-constructed base B, 35 and in the cylinder is mounted to turn a piston having a cylindrical body C, secured on the main shaft D, journaled in suitable bearings carried by the cylinder-heads. The main shaft D is connected outside of the cylinder 40 E by belts or other devices with the machinery to be driven. The inner surface of the cylinder A is formed by the concentric cylindrical segments A' A², located diametrically opposite each other and of different lengths,

45 as will be readily understood by reference to Fig. 1, and the said sections are connected with each other by cylinder-segments A³ A⁴ of the same radius, but eccentric to the concentric segments A' A². The axis of the 50 main shaft D and that of the piston-body C coincides with the axis of the cylinder-segment A', and the peripheral face of the said

piston-body C is in contact with the said segment A'. In the piston-body C are held to slide radially the piston-heads C', arranged in pairs diametrically and rigidly connected with each other by cross-bars C², and the said piston-heads are in contact at their outer ends with the inner surface of the cylinder A, as shown in Fig. 1. The radius of each 60 segment A³ A⁴ is equal to one-half of the aggregate sum of the radii of the segments A' A², and the sum of the radii is equal to the length of a pair of connected piston-heads, and hence the latter are at all times in contact with the inner peripheral surface of the cylinder A.

Chambers F F' are formed on opposite sides of the cylinder A and are connected by openings A⁵ A⁶ in the walls of the segments A³ A⁴ 70 with the interior of the cylinder A, and the said chambers F F' are also connected with the opposite sides of a valve-chamber A⁷, formed on the top of the cylinder A, as plainly shown in Figs. 1 and 2. In this valve-chamber A⁷ is mounted to turn a valve G, carrying at one outer end a handle H under the control of the operator, and the other end of the said valve is connected with the inlet-pipe I, leading to a suitable source of motive-agent supply. The valve G is adapted to connect the inlet-pipe I with either chamber F F', and the said valve also serves to connect either chamber F F' with the exhaust-pipe J, leading from the valve-chamber A⁷ to a suitable 80 place of discharge.

The cross-bars C² for each pair of piston-heads C' are formed with elongated slots C³ for the passage of the main shaft D, and the said piston-heads are fitted to slide in slots 90 C⁴, formed radially in the piston C, and the cross-bars C² extend in recesses C⁵, formed in the faces of the piston C, so that the piston fits snugly in the cylinder A from one cylinder-head to the other, as will be readily 95 understood by reference to Fig. 2.

The operation is as follows: When the valve G is in the position shown in Fig. 1, then steam or other motive agent can pass from the inlet-pipe I through the valve G into the 100 chamber F and from the latter through the opening A⁵ into the interior of the cylinder A, so as to act on the projecting ends of the piston-heads C' and turn the piston in the

direction of the arrow a' . During the time a piston-head C' travels in contact with the segment A² the steam or other motive agent exerts its power on the said piston-head, and 5 when the piston-head reaches the segment A⁴ and passes over the opening A⁶ then the pressure becomes equal on both sides of the piston-head, and hence no resistance is exerted on the said piston-head. The motive 10 agent in the rear of this piston-head can now pass through the opening A⁶ into the chamber F' and from the latter past the valve G into the exhaust-pipe J to be carried to the outside.

15 When it is desired to reverse the engine, it is only necessary for the operator to swing the lever H, so as to connect the inlet-pipe I with the chamber F' and to connect the chamber F with the exhaust-pipe J. The above- 20 described operation is then repeated, the only difference being that the motive agent now exerts itself on the piston-heads in such a manner that the piston is turned in the reverse direction of the arrow a' .

25 From the foregoing it will be seen that during the time the piston-head passes the segment A' there is no pressure whatever on this piston-head, and during the time a piston-head passes over the openings A⁵ or A⁶ the 30 pressure is equal on both sides of the piston-head, so as to relieve the piston of undue back pressure during the time the piston-heads pass over the segments A³, A⁴, and A⁵.

I do not limit myself to the number of 35 slideable piston-heads employed, as the same may be varied—that is, increased or diminished in number—without deviating from the spirit or principle of my invention. I do not limit myself to the particular arrangement of 40 steam (or other motive agent) inlet or outlet, as the same can be varied according to the motive agent used or the engine or when the engine is to be used as a pump or a blower.

The rotary engine described is composed 45 of but few parts and is not likely to get out of order, and the engine can easily be reversed whenever it is desired to do so by the operator manipulating the lever H correspondingly.

50 Having thus described my invention, I claim as new and desire to secure by Letters Patent—

1. A rotary engine comprising a cylinder having its inner surface formed of oppositely-disposed concentric segments of different 55 lengths, and cylinder-segments eccentric to the said opposite concentric segments and connecting the latter with each other, said cylinder-segments being provided with elongated 60 openings, inlet and exhaust chambers on the sides of the cylinder and connected with the interior of the cylinder by the openings in the walls of the eccentric connecting-segments, a valve-chamber at the top of the cylinder 65 and with opposite sides of which the upper ends of the inlet and exhaust chambers connect, a valve in said chamber, and a piston

mounted to turn in said cylinder concentric with the opposite segments and in contact with the smaller one of the said opposite segments, the said piston having diametrical slideable piston-heads in contact at their ends with the inner surface of the cylinder, as set forth. 70

2. A rotary engine comprising a cylinder 75 having its inner surface formed of oppositely-disposed concentric segments of different lengths, and cylinder-segments eccentric to the said opposite concentric segments and connecting the latter with each other, said cylinder-segments being provided with elongated 80 openings, inlet and exhaust chambers on the sides of the cylinder and connected with the interior of the cylinder by the openings in the walls of the eccentric connecting-segments, a piston 85 mounted to turn in said cylinder concentric with the opposite segments and in contact with the smaller one of the said opposite segments, the said piston having diametrical slideable piston-heads in contact 90 at their ends with the inner surface of the cylinder, a valve-chamber on top of the cylinder and with which the inlet and exhaust chambers connect, and a rocking valve in said chamber for controlling the inlet and 95 exhaust pipes of the motive agent to and from either the inlet or exhaust chamber, as set forth.

3. A rotary engine, comprising a cylinder 100 having its inner surface formed of oppositely-disposed concentric segments of different lengths and cylinder-segments eccentric to the said opposite concentric segments and connecting the latter with each other, said cylinder-segments being provided with elongated 105 openings, inlet and exhaust chambers on the sides of the said cylinder and connected with the interior thereof by the openings in the eccentric connecting-segments, and a piston 110 mounted to turn in the said cylinder and having a cylindrical piston-body in contact with the smaller one of the opposite concentric segments, the said body having radial 115 slots leading from its peripheral surface inwardly, and three pairs of piston-heads slideable in the radial slots, each pair of piston-heads being connected with each other by bars arranged on opposite sides of the piston and formed with elongated slots through 120 which extends the piston-shaft, the outer end of the piston-heads being in contact with the inner surface of the cylinder, as set forth.

4. A rotary engine, comprising a cylinder 125 having its inner surface formed of oppositely-disposed concentric segments of different lengths and cylinder-segments eccentric to the said opposite concentric segments and connecting the latter with each other, said cylinder-segments being provided with elongated 130 openings, inlet and exhaust chambers on the sides of the said cylinder and connected with the interior thereof by the openings in the eccentric connecting-segments, a piston mounted to turn in the said cylinder and hav-

ing a cylindrical body in contact with the smaller one of the opposite concentric segments, the said body having radial slots leading from its peripheral surface inwardly, 5 and recesses in its side faces, three pairs of piston-heads slideable in the radial slots, each pair of piston-heads being connected with each other by bars arranged on opposite sides of the piston and formed with elongated slots 10 through which extends the piston-shaft, the outer ends of the piston-heads being in contact with the inner surface of the cylinder, and the said connecting-bars extending in

the recesses formed in the faces of the said piston-body, a valve-chamber on top of the cylinder and with the opposite sides of which the inlet and exhaust chambers connect, and a valve in said chamber, as set forth.

In testimony whereof I have signed my name to this specification in the presence of 20 two subscribing witnesses.

FREDERIC ALBERT PALLÉ.
